UNITED STATES PATENT OFFICE.

FRED A. PUTNAM, OF KEENE, NEW HAMPSHIRE, ASSIGNEE TO MARKEM MACHINE COMPANY, OF BOSTON, MASSACHUSETTS, A CORPORATION OF MASSACHUSETTS.

MARKING MACHINE.

Original application filed July 3, 1924, Serial No. 723,974. Divided and this application filed February 29, 1926. Serial No. 89,542.

This invention relates to marking machines of the type which comprise a work support and a printing head carrying type characters and movable toward and from the work support to make the printed impression on the work.

The object of the invention is to provide a novel means for supporting and giving movement to the printing head and the novel features thereof will be more fully herein-after set forth and then pointed out in the appended claims.

In the drawings, Fig. 1 is a side view of a marking machine embodying the invention and showing the type in inking position;

Fig. 2 is a similar view showing the printing head in position to make a printed impression.

1 indicates the frame of a marking machine embodying my invention, and 2 indicates the work support on which the work or sheet 3 to be printed is placed. The printing is done by type members 4 that are carried by a printing head 5, the latter being movable toward and from the work support 2. The present invention relates to novel means for giving the printing head 5 its movement.

This printing head is shown as carried by the lower end of an arm 6, the upper end of which is pivotally connected at 7 to one end of a lever 8, the latter being pivoted at 9 to the frame 1. The lever 8 extends beyond the pivot point 9 and the extended end has a pulling spring 10 connected thereto which tends to raise the front end of the lever to which the printing head is secured.

The movement of the printing head toward and from the work support is controlled by a toggle lever device comprising the two toggle elements 11 and 12 which are pivoted together at 13. The toggle element 11 is pivoted at 14 to the frame 1 and the toggle element 12 is pivoted at 15 to the arm 6.

16 indicates a pulling spring which is connected at one end to the pivotal connection 13 of the toggle lever device and at the other end is connected to the frame, preferably to the pivotal connection 9. The spring 16 thus has a normal tendency to break the toggle 11, 12 and to swing it into the position shown in Fig. 1. When the toggle

is straightened, as shown in Fig. 2, the printing head will be in printing position and the breaking of the toggle due to the pulling action of the spring 16, augmented by the action of the spring 10, will swing the arm 6 upwardly and backwardly thus removing it from the work support and carrying it back of the work support, as shown in Fig. 1.

When the toggle is straightened the printing head will be brought back into printing position, as shown in Fig. 2. The straightening of the toggle is accomplished manually by means of a treadle, not shown, which is connected to the toggle element 11 by means of a link or connection 17.

The toggle device is provided with a stop constructed so that it cannot be bent or broken below its straightened position. This stop is in the form of an abutment 18 carried by the toggle member 12 and an adjustable screw 19 screw-threaded in a boss 20 carried by the toggle member 11. The screw 19 will be adjusted so that it will engage the abutment when the toggle elements have been swung into their straightened position.

In the operation of the device and assuming that the printing head is in its retracted position shown in Fig. 1 a downward pull on the connection 17 will first straighten the toggle thereby swinging the lower end of the arm 6 forwardly and carrying the printing head 5 forwardly into a position over the work support. Continued downward pull on the connection 17 will then swing the straightened toggle and the lever 8 downwardly thus bringing the type characters against the work as shown in Fig. 2.

When the toggle lever is straightened the distance between the pivots 14 and 15 is the same as the distance between the pivots 9 and 7 and, therefore, after the toggle lever has been straightened said straightened toggle and lever 8 operate with a parallel ruler motion. The pivot 9 is vertically over the pivot 14 and when the straightened toggle and the lever 8 are swung downwardly the printing head will, therefore, be given a vertical movement which is at right angles to the surface of the work support and the type, therefore, will be brought squarely against the work. During this downward parallel ruler motion the spring 10 is extend-

ed and as soon as the pressure on the treadle is released said spring 10 will swing the lever 8 and the straightened toggle upwardly with a parallel ruler motion thus separating the type from the work in a vertical direction and thereafter the spring 16 will operate to break the toggle and to swing the raised printing head upwardly into its retracted position, shown in Fig. 1.

10 As a result of this construction the motion of the printing head toward the work support is first in a forward direction to bring the printing head directly over the work support and then in a downward direction 15 to bring the type squarely against the work. Similarly, during the retracting movement the printing head will first be moved directly away from the work in a vertical direction and will then be swung backwardly.

20 An advantage resulting from this construction is that the final movement of the printing head which brings the type against the work and also the initial withdrawing movement is in a direction at right angles 25 to the work support, which is essential in making a clear printed impression.

21 is an adjustable stop against which the toggle member 11 rests when the parts are in their normal raised position.

30 The type are inked by an inking pad 22 which is constructed to be brought against the type when the printing head is in its normal raised position. This inking pad is secured to a swinging arm 23 which is pivoted at 24 to an arm 25 extending from the frame. The swinging member 23 is connected to the printing head 5 by means of a link 26, the latter being pivoted to the arm at 27 and to the printing head at 28.

40 The construction and proportion of the parts 23, 26 is such that when the printing head is swung from its operative position shown in Fig. 2 to its raised position shown in Fig. 1 the member 23 carrying the inking pad will be raised thus bringing the inking pad against the type as shown in Fig. 1.

45 When the printing head is moved into its operative position, as shown in Fig. 2, the member 23 is swung downwardly thus separating the pad from the type and this separating movement occurs as the printing head begins to move forwardly so that the type will not have a dragging movement across the face of the inking pad. Similarly, when the printing head returns to the 55 position shown in Fig. 1 the inking pad will be given an upward movement during the last part of the movement of the printing head thus bringing the inking pad 60 squarely against the type.

65 It will be seen from the above that I have provided a simple mechanism for operating the printing head by which said head is not only brought against the work support and raised therefrom in a direction at

right angles to the work support, but is also given a backward movement so as to carry it back of the work support. The advantage of this is that when the printing head is raised it is back of the work support and so that the operator may freely remove the printing sheet from the work support and place a new sheet thereon.

The mechanism has the further advantage 75 that it is extremely simple in construction.

This application is a division of application Serial No. 723,974, filed July 3rd, 1924.

I claim:

1. In a marking machine, the combination with a frame, of a printing head having an arm rigid therewith and rising therefrom, a lever pivoted to the upper end of the arm and to the frame, a toggle member pivoted at one end to the frame and at the other end to the arm, and means to straighten the toggle thereby to swing the printing head forwardly and then to move the toggle downwardly thereby to bring the printing head into printing position.

2. In a marking machine, the combination with a frame, of a printing head having an arm rigid therewith and rising therefrom, a lever pivoted to the upper end of the arm and to the frame, a toggle member pivoted at one end to the frame and at the other end to the arm, said toggle member being constructed to break in one direction only, means to straighten the toggle lever thereby to swing the printing head forwardly and then to swing said lever downwardly thereby to bring the printing head into printing position.

3. In a marking machine, the combination with a frame, of a printing head having an arm rigid therewith and rising therefrom, two parallel ruler members by which the arm is supported, means for actuating said members to give the printing head a vertical movement, one of said members being a toggle device capable of breaking in one direction only.

4. In a marking machine, the combination with a frame, of a printing head having an arm rigid therewith and rising therefrom, two parallel ruler members by which the arm is supported, means for actuating said members to give the printing head a vertical movement, one of said members being a toggle device capable of breaking in one direction only, a pivoted ink-pad-carrying member, an inking pad carried thereby, and means connecting said member to said printing head whereby the inking pad is brought against the type when the printing head is raised.

5. In a marking machine, the combination with a frame, of a work support, a printing head having an arm rigid therewith and rising therefrom, a lever pivoted to the upper end of the arm and to the frame, a spring

acting on said lever tending to raise the printing head, a toggle member pivoted at one end to the frame and at the other end to the arm, said toggle being arranged to break in one direction only, a spring acting on said toggle and tending to break the same, and manually-operated means for first straightening the toggle thereby swinging the printing head forwardly and then to swing the toggle downwardly to move the printing head against the work support.

6. In a marking machine, the combination with a frame, of a work support, a printing head having an arm rigid therewith and rising therefrom, a lever pivoted to the upper end of the arm and to the frame, a spring acting on said lever and tending to raise the printing head, a toggle

member pivoted at one end to the frame and at the other end to the arm, said toggle being arranged to break in one direction only, a spring acting on said toggle and tending to break the same, and manually-operated means for first straightening the toggle thereby swinging the printing head forwardly and then to swing the toggle downwardly to move the printing head against the work support.

In testimony whereof, I have signed my name to this specification.

FRED A. PUTNAM.
